UNITED STATES PATENT OFFICE

2,563,032

CIGAR BUNCHING MACHINE

Karl Erik Granstedt, Stockholm, Sweden, assignor to Areenco Aktiebolag, Stockholm, Sweden, a Swedish joint-stock company

Application February 21, 1946, Serial No. 649,317

1 Claim. (Cl. 131—44)

1 This invention relates to improvements in cigar bunching machines and it is concerned particularly with machines of the type in which the tobacco filler is rolled over a lead plate or table by a looped apron and roller cooperating therewith.

It is an object of the invention to provide a machine of the kind referred to with a perfectly operating safety device, preventing accidents which are likely to occur at manually served parts of said machine. The nature and characteristic features of the invention will be more readily understood from the following description taken in connection with the accompanying drawings in which:

Fig. 1 is a front elevational view of a cigar bunching machine embodying the main features of the invention;

Fig. 2 is a vertical sectional view on the line II—II of Fig. 1;

Fig. 3 is a plan view on an enlarged scale of the machine;

Fig. 4 is a front view on a still more enlarged scale of the main features of the invention;

Fig. 5 is a sectional view on line V—V of Fig. 4; and Fig. 6 is a sectional view similar to Fig. 5 but showing some parts in other operating positions.

Referring to the drawings, the machine has a bunch rolling table 1 upon which is placed a bunch rolling apron 2. At its front end the apron 2 is by means of wing nuts 3 secured to the front end of the table 1. At its rear end the apron 2 is by means of wing nuts 4 secured to a bar 5 extending across the machine and formed integral with two rocking arms 6 which are pivoted on a pin 55 in the machine frame 7 and controlled by a rocking mechanism not shown, because it does not form part of this invention.

A mechanism for delivering measured quantities of filler tobacco to the pocket 8 formed by the apron 2 comprises a funnel 9. The funnel 9 is raised and lowered at predetermined intervals, and for this purpose it is mounted on brackets 10 which in turn are mounted upon vertical rods 11. The rods 11 are slidably mounted at their upper ends in extensions 12 projecting from a bracket 54 on the machine frame 7 and at their lower ends in said frame. The lowermost end of one of the rods 11 is rigidly secured in a socket 13 to which a link 14 is pivoted as at 15, which link is pivoted at its other end as at 16 to the outer free end of a arm 17. The other end of the arm 17 is journalled on a transversely extending shaft 18 and on the outer free end of said arm 17 there is mounted a roller 19 which engages in a groove 20 in a cam 21 which is secured to the main shaft

2 22 of the machine. It will be seen that the funnel 9 will make one complete cycle of movements for each rotation of the main shaft 22.

To obtain the delivery of a measured quantity 5 of filler tobacco at the proper time a block 23 is mounted within the funnel 9 in such manner as to be capable of vertical movement with respect thereto. The upper end of the block 23 is connected by means of a rod 24 to a yoke bracket 25 which is carried by the uppermost ends of two vertical rods 26 which are slidably mounted in a manner similar to the rods 11 at their upper ends in the bracket 12 and at their lower ends in the machine frame 7. The lowermost end of one of the rods 26 is secured to a socket 27 to which a link 29 is pivotally connected as at 28 the other end of which link being pivotally connected as at 30 to the outer free end of a lever 31. The other end of the lever 31 is pivotally mounted on the 10 transversely extending shaft 18 and between the ends of said lever 31 there is mounted a roller 32 which engages in a groove 33 in a cam 34 which cam is also secured to the main shaft 22 of the machine.

25 The tobacco filler delivered from the funnel 9 to the pocket 8 of the apron 2 is in usual manner wound up by a bunch roller 35 into a binder placed on the apron 2 on the table 1. The bunch roller 35 is vertically adjustably and rotatably mounted on two brackets 36 each of which are secured to one of the upper ends 37 of a bifurcated lever arm 38 which ends project upwards through slots 53 in the machine frame. The lever arm 38 is pivotally journalled on a shaft 50 and provided with a roller 51 which engages in a 30 groove 49 in a cam 39 secured to the shaft 22 so that the bunch roller 35 performs a movement forth and back over the bunch rolling table 1 after each delivery of a filler tobacco to the pocket 8 of the bunch rolling apron 2.

35 Each bracket 36 has a pair of lugs 40 in which is slidably mounted a rod 41. To the front ends of both the rods 41 is secured a yoke 42 to which is secured a plate 43. The rearmost lugs 40 and the front ends of the rods 41 are interconnected by tension springs 44. When the bunch roller 35 and thereby also the brackets 36 occupy the retracted position as shown in Figs. 3 and 5 the rear ends of the rods 41 abut each a shoulder 45 on the machine frame. Thereby the springs 44 are tensioned and the plate 43 remains in a position in front of the lower end of the funnel 9 and the pocket 8 of the apron 2 so that the operator cannot put his fingers into the pocket 8 below the raised funnel 9. Any risk of accident will

thus be obviated. When the funnel 9 has delivered a filler tobacco to the pocket 8 and been raised the bunch roller 35 starts advancing whilst the plate 43 serving as a protective shield will still remain in its position as shown in Fig. 5. Thereby the springs 44 are contracted until the ends 46 of the foremost lugs 40 abut the shoulders 47 of the heads 48 of the rods 41. At this moment the bunch roller 35 has advanced into a position close behind the plate 43. Consequently, the operator's fingers cannot be jammed between the bunch roller 35 and the rear end of the bunch rolling table. On continued forward movement of the roller 35 to the position shown in Fig. 6, the rods 41 and consequently also the protective shield 43 will advance over the bunch rolling table 1. When the bunch roller 35 reaches its foremost position the arms 6 are swung back in known manner so that the apron 2 is straightened as shown in Fig. 6. When retracting the bunch roller 35 the protective shield 43 will follow same until the rear ends of the rods 41 abut the shoulders 45. At this moment the protective shield has reached its initial position as shown in Figs. 2 and 5 and on continued retractive movement the springs 44 are tensioned and the arms 6 are swung forward to slacken the apron 2. Thereby a complete cycle of operation has been performed.

I claim:

In a cigar bunching machine, a bunch rolling

5

table, a bunching apron, a bunching roller co-operating with said apron by reciprocating movement over said table from and into a retracted position, movable mounting means for said bunching roller, distributing means movable towards said apron for depositing filler tobacco thereon, an upright protective shield comprising a plate movably mounted on and relative to said mounting means, means for moving said shield in advance of said bunching roller closely above said apron and for retracting said shield into an upright protective position in front of said distributing means and closely above said apron, and means for then moving said distributing means towards said apron behind said shield.

KARL ERIK GRANSTEDT.
